INVENTOR

Philip Doflein

UNITED STATES PATENT OFFICE.

PHILIPP DOFLEIN, OF PHILADELPHIA, PENNSYLVANIA, ASSIGNOR TO GUSTAVIS STORM AND FRANCES STORM, OF SAME PLACE.

DESIGN FOR PERFUME-BOTTLES.

Specification forming part of Design No. 6,021, dated August 13, 1872.

Specification describing a Design for a Perfume-Bottle, invented by PHILIPP DOFLEIN, of the city and county of Philadelphia and State of Pennsylvania.

The nature of my design is fully represented in the accompanying photographic illustration, to which reference is made.

My design consists in making the bottle of a flat elongated form, and ornamenting it with curved lines somewhat on the Corinthian style.

What I claim is—

The design for a perfume-bottle, as shown and described.

Witnesses: PHILIPP DOFLEIN.

ISAAC R. OAKFORD,

ISAAC TOWNSEND.
